UNITED STATES PATENT OFFICE.

FREDRICK HANSON AND CHARLES FREIHOFER, OF PHILADELPHIA, PENNSYLVANIA.

DESIGN FOR A LOAF OF BREAD OR SIMILAR ARTICLE.

SPECIFICATION forming part of Design No. 33,609, dated November 20, 1900.

Application filed September 29, 1900. Serial No. 31,585. Term of patent 14 years.

To all whom it may concern:

Be it known that we, FREDRICK HANSON and CHARLES FREIHOFER, citizens of the United States, and residents of Philadelphia, Pennsylvania, have invented and produced a certain new and original Design for a Loaf of Bread or Similar Article, of which the following is a specification.

Our design for a loaf of bread or similar article is clearly illustrated in the accompanying drawing, the figure of which represents the loaf in perspective.

The essential feature of the design is a loaf elongated in form, having corrugated edges and rounded upper surface and having a figure on the upper surface.

A is the loaf, rounded at each end a a. The body portion of the loaf has a series of vertical ribs rounded to form a corrugated surface, giving the effect clearly illustrated 20 in the drawing. The upper portion of the loaf is rounded, as shown, and has a representation of a human figure thereon in relief.

We claim—

The design for a loaf of bread or similar article as herein described and as illustrated 25 in the accompanying drawing.

In testimony whereof we have signed our names to this specification in the presence of two subscribing witnesses.

FREDRICK HANSON.
CHARLES FREIHOFER.
